(57) **CLAIM**

The ornamental design for a flow timer for gas grill, as shown and described.

DESCRIPTION

FIG. 1 is a top plan view of a flow timer for gas grill showing our new design;

FIG. 2 is a bottom plan view thereof;

FIG. 3 is a right side elevation view thereof;

FIG. 4 is a left side elevation view thereof;

FIG. 5 is a front elevation view thereof, the opposite side being a mirror image of the shown; and,

FIG. 6 is an isometric view thereof.
